UNITED STATES PATENT OFFICE.

HERMANN V. FENGLER, OF WEST PHILADELPHIA, PENNSYLVANIA, ASSIGNOR TO
UNDERWOOD TYPEWRITER COMPANY, OF NEW YORK, N. Y., A CORPORATION
OF DELAWARE.

TYPE-WRITING MACHINE.

1,109,671.

Specification of Letters Patent. Patented Sept. 8, 1914.

Application filed June 24, 1914. Serial No. 846,933.

To all whom it may concern:

Be it known that I, HERMANN V. FENGLER, a citizen of the United States, residing in West Philadelphia, in the county of Philadelphia and State of Pennsylvania, have invented certain new and useful Improvements in Type-Writing Machines, of which the following is a specification.

This invention relates to typewriting machines and more particularly to means for rotating the platen first in one direction to bring a work-sheet thereon into position to be removed, and then in the reverse direction to bring a new work-sheet into position to be written upon.

In making typewritten entries upon a series of bills or other work forms, it is customary to make a record copy on a record sheet which remains on the machine to receive the duplicate entries of a number of bills. When the typewritten entries on a bill have been completed, the platen is rotated backwardly into position to permit the bill to be removed, and to receive the succeeding bill which is then placed on the machine and the platen rotated forwardly to bring the new bill into position to be written upon. As the record sheet moves with the platen during both its backward and forward rotations, the forward rotation must be through a somewhat greater angle than the backward rotation, to provide suitable space between the entries on the record-sheet.

In accordance with the present invention, a driver is provided for rotating the platen in both directions, by a movement of the driver in one direction, said driver operable during the initial portion of its driving stroke to rotate the platen backwardly for bringing a work-piece into position to be moved from the machine, and operable during the succeeding portion of its driving stroke or movement in the same direction to rotate the platen forwardly through a somewhat greater angle for bringing a new work-piece into position to be written upon, and positioning the record-sheet to receive the record copy of the new entry. The driver may be returned to initial position without rotating the platen.

In practicing the invention, the driver may comprise a rod slidably mounted on the paper carriage to reciprocate thereon, said

rod carrying a pair of parallel rack-carrying bars in which are adjustably mounted racks, arranged to drive a pinion connected to the platen for rotating the latter, said racks engaging opposite sides of the pinion to rotate it in opposite directions. One of the racks, being in advance of the other, engages the pinion during the initial advance movement of the plunger to rotate the platen backwardly to bring a work-piece thereon into position for removal from the machine. and after the first rack passes beyond the pinion, the other rack engages the opposite side of the pinion and rotates the platen forwardly to position a new work-piece thereon. The parallel rack-supporting bars or carriers are connected by links, and during the advance of the driver, said bars are engaged by cams which throw the said bars toward each other into position to engage the racks with the pinion, and rotate the platen, but during the return of the driver, said cams are swung out of holding position and permit the parallel bars to be separated by springs and hold the racks away from the pinion, so that the driver is returned without rotating the platen. Each rack is adjustable in its supporting bar to vary the amplitude of rotation of the platen thereby, and graduated scales may be provided to show the position of the racks, and indicate the extent the platen will be rotated by the driver. The scales are preferably graduated to indicate the number of line-spaces through which the platen will be rotated. An adjustable gage limits the operating stroke of the driver, and co-operates with the rack to positively prevent backward rotation of the platen beyond the point for which the gage is set. The driver may be held in its intermediate position after the first rack has rotated the platen backwardly, and before the second rack has come into operation by means of a spring-actuated cam engaging with a detent adjustable with the first rack.

Other features and advantages will hereinafter appear.

This application shows certain features of invention also disclosed in my co-pending application No. 846,934, filed June 24, 1914.

In the accompanying drawings, Figure 1 is a sectional elevation view of an Underwood typewriting machine with the present invention applied thereto. Fig. 2 is a frag-

mentary sectional view as indicated by the section line 2-2 on Fig. 1. Figs. 3, 4 and 5 are fragmentary views similar to Fig. 1, but showing the driver in different positions. 5 Fig. 3 shows the driver in an intermediate position assumed during the forward or driving stroke, the first rack having rotated the platen backwardly, and the second rack just commencing to advance the platen. 10 Fig. 4 shows the driver having completed its driving stroke. Fig. 5 shows the driver at an intermediate position during its return movement, the racks being held away from the pinion. Fig. 6 is a sectional detail 15 view showing the upper rack and its carrier, and the adjustable stop thereon. Fig. 7 is a front view of the same. Fig. 8 is a fragmentary perspective view showing the lower rack and carrier and the rack-holding clip. 20 Fig. 9 is a perspective view of said clip and the detent-holding cam thereon. Fig. 10 is a sectional view of a modification in which the lower rack is placed up-side-down in its support, so as to be inoperative, and permit 25 the upper rack alone to drive the platen. Fig. 11 is a detail plan view showing the scale on the upper rack bar.

The platen 1 is mounted on an axle 2 journaled in the ends 3 of the platen frame, 30 which frame also comprises an inclined paper shelf 4 connecting the ends 3, and located at the intake side of the platen. The platen frame is supported on and forms part of the paper carriage 5 mounted to travel 35 on guide rails 6 on the machine frame 7. Type-bars 8, operated in the usual way, strike against the front face of the platen. Front and rear feed rolls 9 and 10 are supported on levers 11 pivoted on a rod 12 and 40 are spring-held against the under surface of the platen. Said feed rolls may be lifted from the platen by cams on a key-operated rock shaft 13, said cams engaging arms 14 of the levers 11 to spread said arms and lift 45 the feed rolls from the platen.

The construction and operation of the above-named parts may be the same as is common in the commercial Underwood type-writing machine.

50 The mechanism for rotating the platen backwardly and forwardly in billing or other work in which bills or the like are placed on the machine *seriatim*, will now be described. Such mechanism comprises a reciprocating driver 15 which as shown, 55 comprises a rod slidably mounted in bearings 16 and 17 on the paper carriage. The rod 15 carries a pair of parallel guide bars or carriers 18 and 19, in which are slidably 60 mounted upper and lower rack bars 20 and 21. Links 22 are connected at their upper ends by pivots 23 to the rod 15, the lower ends of said links being pivoted to the lower rack carrier 19, and links 24 are connected 65 to the upper rack carrier 18 and to the links

22 at a point between said carriers. The links 22 therefore form a swinging support for the carriers 18 and 19, while the links 22 and 24 form a toggle connection between said carriers, permitting the latter to be moved toward each other. The racks 20 and 21 are provided with rack teeth to drive a pinion 25 fixed to the platen axle 2, or otherwise connected to drive the platen. 70

The rack bars 20 and 21 are slidably mounted for longitudinal adjustment in channels formed in the carriers 18 and 19, and, as shown for example in Fig. 8, the rack bars may be formed with ribs 26, which slide in grooves 27 formed in the side walls 80 of said channels. The rack 21 is held in its adjusted position by means of a U-shaped spring clip or holder 28, having a lug 29 thereon to engage with any one of a series of notches 30 in the rack-supporting bar 19, 85 said holder being secured, as by means of a pin 31 to the forward end of the rack 21. By grasping the holder 28 between the thumb and finger, the holding lug 29 may be sprung inwardly to release the rack and 90 permit it to be adjusted, and when released, the lug will be sprung into a holding notch 30. The holder 28 may be provided with an off-set or rib 32 to slide in the groove 27. The upper rack 20 may be provided with a 95 latch or holding clip 33 similar to the holder 28 for maintaining the rack 20 in any position of adjustment.

In Fig. 1, the driver is shown in its initial or normally operative position. A ledger sheet or other record sheet 34, is shown occupying a position on the platen reached after the record entries from a number of bills have been made thereon, and a bill or other work-piece 35 and carbon sheet 36 are shown in the position they assume when placed on the paper shelf 4 with their leading edges at the bite of the rear pressure roll 10 and the platen, preparatory to being fed forwardly into position to be written upon. The driver is held in its normal position of rest by a coil spring 37 mounted thereon between the bearing 16 and a handle 38 on the upper end of the driver, the upper link 22 being held against the lug 16. When the operator presses the handle 38, the driver is advanced, and the leading edges of the bars 18 and 19 engage the projecting ends of cams 39, which, by retarding said bars, cause the latter to be swung rearwardly 110 relative to the rod 15, so that the links 22 and 24 assume the inclined position shown in Fig. 4. In other words, the advance of the rod 15, while the parallel bars are held against forward movement, causes the links 22 and 24 to assume an inclined position, thereby drawing the parallel bars toward each other, so that the rack teeth can engage the pinion 25. The rack carriers, after being thrown into operative position, ride 115 120 125 130

along the cams 39 and are held in operative position by said cams during the entire advance or driving stroke of the driver. As the rack carriers are thrown into operative position, the first or leading rack 21 at once engages the pinion 25 and as the driver advances, rotates the platen backwardly until the pinion runs off the rack, at which point the driver is held by a detent 40, which snaps into a notch 41, formed in a holding cam 42 at the end of the rack 21. Said cam as clearly shown in Figs. 8 and 9, forms an extension of the holder 28, said cam projecting downwardly through a slot 43 in the bar 19. The driver is held by the detent 40 while the bill or other work-sheet, which has been carried back onto the shelf 4 by the backward rotation of the platen, is removed and a new sheet substituted. The detent 40 has sufficient holding power to prevent movement of the driver by the spring 37 and also prevents accidental rotation of the platen at this time. The operator now pushes the driver forwardly from its intermediate position, the detent 40 on the spring arm 44 being thereby forced out of the notch 41 (see Fig. 3) and the upper rack 20 engages the driving pinion 25, and rotates the platen forwardly until a stop 45 on the guide bar 18 strikes the driving pinion and locks the platen against further forward rotation. The stop 45 is adjustable on the bar 18, and is held in adjusted position by a set screw 46 as shown in Fig. 6. The stop 45 is adjusted to such a position that the forward rotation of the platen by the driver will bring the work-sheet into position to receive the first line of writing. The lower rack 21 is adjusted to effect a backward rotation of the platen through a somewhat smaller angle than the forward rotation thereof by the driver. This is in order that the record sheet 34, which moves backwardly and forwardly with the platen, may be carried forwardly a sufficient distance when a new bill is placed on the platen to provide a space on the record sheet between the new record and the preceding record. In practice, this space is usually equal to two line-spaces, but may be varied as desired. A graduated scale 47 on the guide bar 19 facilitates the adjustment of the rack 21 to any desired position, the scale graduations preferably corresponding to the line-space rotations of the platen. Also the spacing of the rack teeth and teeth on the driving pinion is preferably equal to the spacing of the scale markings. In other words, each rack tooth advances the platen through a line-space distance, that is, the distance through which the platen is rotated at each operation of the usual line-space mechanism (not shown). The rack bar 20 may be provided with a graduated scale 48 (Fig. 11) along which the gage 45

is adjustable, the scale indicating the number of line-spaces through which the platen will be rotated forwardly in bringing the gage 45 up to the pinion 25. The scale 48 may be on the upper face of the rack bar 20, and the bar 18 may be formed with an open slot or channel 20^a in which the rack bar is guided. After the driver has completed its driving stroke, a slight movement thereof in the reverse direction, which may be effected either by the spring 37, when the handle is released by the operator, or by a pull on the handle, the cams 39 are rotated about their pivots 49 to the Fig. 5 position, and permit springs 50 to spread the guide bars 18 and 19 and free the racks from the driving pinion, so that the driver may return to its initial position without rotating the platen. The cams 39 are lightly held by springs 51 in the Fig. 1 position against stop pins 52 and the pressure of said bars against the cams is in a direction to hold the cams against the stop pins 52. A very slight forward movement however, of the driver swings said cams sufficiently to permit the guide bars, under the influence of the springs 50, to snap the cams to the Fig. 5 position, so that the pinion 25 is released without any material rotation as the driver commences its return movement. The springs 50, as shown in Fig. 6, may be mounted on guide pins 53 on lugs 54 projecting laterally from the guide bars.

If desired, the lower rack bar 21 may be removed, and the upper rack bar 20 alone used. The driver may thus be used in placing envelops, bills, or other work-pieces on the platen *seriatim*.

In Fig. 10 a slightly modified form of lower rack bar 21^a is shown in an inverted position in the guide 19, in which position it is out of the way, permitting the upper rack to be used alone, but the rack bar 21^a may be reversed, and used in connection with the upper rack bar when it is desired to drive the platen in both directions. In this form the rack bar 21^a is provided with a rib 26 along each side and the guide bar 19 is provided with correspondingly positioned grooves 27.

Variations may be resorted to within the scope of the invention, and portions of the improvements may be used without others.

Having thus described my invention, I claim:

1. In a typewriting machine, the combination with a platen, of a driver for rotating the platen first in one direction, and then in the other direction during the movement of the driver in one direction, said driver returnable to initial position without rotating the platen during its return movement.

2. The combination with a platen, of a driver for rotating the platen, said driver

- comprising racks, and gearing between said racks and the platen, one of said racks operable through said gearing to rotate the platen in one direction, and the other rack operable through said gearing to rotate the platen in the opposite direction.
3. In a typewriting machine, the combination with a roller platen, of a gear pinion connected to rotate the platen, a reciprocating driver to rotate said pinion, said driver comprising parallel supporting bars, links connecting said bars, racks adjustably mounted in said bars, one of said racks located in advance of the other to engage said pinion and rotate the platen in one direction during part of the advance movement of the driver, the other rack being in position to engage said pinion and rotate the platen in the opposite direction during a further advance movement of the driver, cams in position for holding said supporting bars in operative position during the advance of the driver, said cams mounted to swing out of said holding position during the return of the driver, springs to hold said supporting bars out of operative position during the return of the driver, a detent to hold the driver in an intermediate position after the first rack has operated but before the second rack has operated, an adjustable stop to limit the advance movement of the driver, and a spring to hold the driver in its normal position.
4. In a typewriting machine, the combination with a roller platen, of a gear pinion connected to rotate the platen, a reciprocating driver to rotate said pinion, said driver comprising parallel supporting bars, links connecting said bars, and racks adjustably mounted in said bars, one of said racks located in advance of the other to engage said pinion and rotate the platen in one direction during part of the advance movement of the driver, the other rack being in position to engage said pinion and rotate the platen in the opposite direction during a further advance movement of the driver.
5. In a typewriting machine, the combination with a roller platen, of a gear pinion connected to rotate the platen, a reciprocating driver to rotate said pinion, said driver comprising parallel supporting bars, links connecting said bars; racks adjustably mounted in said bars, one of said racks located in advance of the other to engage said pinion and rotate the platen in one direction during part of the advance movement of the driver, the other rack being in position to engage said pinion and rotate the platen in the opposite direction during a further advance movement of the driver, cams in position for holding said supporting bars in operative position during the advance of the driver, said cams mounted to swing out of said holding position during the return of the driver, means to hold said supporting bars out of operative position during the return of the driver, and means to hold the driver in intermediate position after the first rack has operated but before the second rack has operated.
6. In a typewriting machine, the combination with a roller platen, of a gear pinion connected to rotate the platen, a reciprocating driver to rotate said pinion, said driver comprising parallel supporting bars, links connecting said bars to each other and to said support rod, racks mounted for adjustment longitudinally in said bars, one of said racks located in advance of the other to engage said pinion on one side and rotate the platen in one direction during part of the advance movement of the driver, the other rack being in position to engage said pinion on the opposite side and rotate the platen in the opposite direction during the further advance movement of the driver, cams for holding said supporting bars in operative position during the advance of the driver, said cams mounted to move out of holding position during the return of the driver, means to hold said supporting bars out of operative position during the return of the driver, and means to hold the driver in intermediate position after the first rack has operated but before the second rack has operated.
7. In a typewriting machine, the combination with a roller platen, of a gear pinion connected to rotate with the platen, a driver comprising a rod mounted for reciprocating movement, said driver comprising parallel rack supporting bars, links connecting said bars to each other and to said support rod, racks mounted for adjustment longitudinally in said bars, one of said racks located in advance of the other to engage said pinion on one side and rotate the platen in one direction during part of the advance movement of the driver, the other rack being in position to engage said pinion on the opposite side and rotate the platen in the opposite direction during the further advance movement of the driver, cams for holding said supporting bars in operative position during the advance of the driver, said cams mounted to move out of holding position during the return of the driver, means to hold said supporting bars out of operative position during the return of the driver, and means to hold the driver in intermediate position after the first rack has operated but before the second rack has operated.
8. In a typewriting machine, the combination with a roller platen, of a gear pinion connected to rotate with the platen, a driver comprising a rod mounted for reciprocating movement, said driver comprising parallel rack supporting bars, links connecting said bars to each other and to said support rod,

and racks mounted for adjustment longitudinally in said bars, one of said racks located in advance of the other to engage said pinion on one side and rotate the platen in one direction during part of the advance movement of the driver, the other rack being in position to engage said pinion on the opposite side and rotate the platen in the opposite direction during the further advance movement of the driver.

9. In a typewriting machine, the combination with a roller platen, of a gear pinion connected to rotate with the platen, a driver comprising a rod mounted for reciprocating movement, said driver comprising parallel rack supporting bars, links connecting said bars to each other and to said support rod, racks mounted for adjustment longitudinally in said bars, one of said racks located in advance of the other to engage said pinion on one side and rotate the platen in one direction during part of the advance movement of the driver, the other rack being in position to engage said pinion on the opposite side and rotate the platen in the opposite direction during the further advance movement of the driver, cams for holding said supporting bars in operative position during the advance of the driver, said cams mounted to move out of holding position during the return of the driver, means to hold said supporting bars out of operative position during the return of the driver, means to hold the driver in intermediate position after the first rack has operated but before the second rack has operated, and scales on said supporting bars to indicate the position of the racks thereon.

10. In a typewriting machine, the combination with a roller platen, of a gear pinion connected to rotate with the platen, a driver mounted for forward and backward movement, said driver comprising racks to rotate said pinion, one of said racks located in advance of the other to engage said pinion and rotate the platen in one direction during part of the forward throw of the driver, the other rack being in position to engage said pinion and rotate the platen in the opposite direction during a further forward movement of the driver, and means for holding said racks in operative position during the advance of the driver and in inoperative position during the return of the driver.

11. The combination with a paper carriage and platen, of a driver having a limited backward and forward movement, said driver comprising means operable during a portion of its movement in one direction to rotate the platen backwardly and during a further portion of its movement in said direction to rotate the platen forwardly.

12. The combination with a paper carriage and platen of a driver having a limited backward and forward movement, said

driver comprising means operable during a portion of its movement in one direction to rotate the platen backwardly, and during a further portion of its movement in said direction to rotate the platen forwardly, and mechanism to move said platen-rotating means to inoperative position and permit the return of the driver without rotating the platen.

13. The combination with a paper carriage and platen, of a gear connected to drive the platen, a driver mounted to have an advance and return movement on the carriage, said driver comprising teeth to engage said gear and rotate the platen in one direction during a portion of the advance movement of the driver, and other gear teeth to engage said gear and rotate the platen in the opposite direction during a further portion of the advance movement of the driver, said gear teeth movable to inoperative position during the return of the driver.

14. The combination with a platen, of a reciprocating driver, and gearing between the platen and driver, said driver comprising racks operable one after the other, to drive the platen first in one direction and then in the opposite direction during a movement of the driver in one direction.

15. The combination with a platen, of a reciprocating driver, gearing between the platen and driver, said driver comprising racks operable one after the other, to drive the platen first in one direction and then in the opposite direction during a movement of the driver in one direction, and means to automatically move said racks to inoperative position after they have driven the platen and thereby prevent rotation of the platen during the return movement of the driver.

16. In a typewriting machine, the combination with a platen, of a platen-rotating device comprising means operable during a movement of said device in one direction to rotate the platen first in one direction through a predetermined angle, and then in the reverse direction through a different angle, and means to limit the movement of said device in both directions.

17. In a typewriting machine, the combination with a platen, of a platen-rotating device comprising means operable during a movement of said device in one direction to rotate the platen first in one direction through a predetermined angle, and then in the reverse direction through a different angle, said platen-rotating means being adjustable to vary the extent of rotation of the platen in both directions.

18. In a typewriting machine, the combination with a platen, of a platen-rotating device operable during a portion of its movement in one direction to rotate the platen backwardly and during another portion of its movement in said direction to ro-

- tate the platen forwardly through a greater angle than it was rotated during said backward rotation, said platen-driving means being returnable to initial position without rotating the platen.
19. In a typewriting machine, the combination with a roller platen, of a reciprocating platen driver comprising a rack to rotate the platen in one direction as the driver advances, and a second rack to rotate the platen in the reverse direction during a further advance of the driver, and a detent to yieldingly hold the driver in an intermediate position after one rack has operated, and before the other rack is brought into operation.
20. The combination with a platen, of a pinion connected to rotate the platen, a reciprocating driver comprising racks to run on opposite sides of the pinion and rotate the platen in opposite directions, means to automatically hold the racks in operative position during the movement of the driver in one direction, and means to automatically move said racks to inoperative position during the movement of the driver in the reverse direction.
21. The combination with a roller platen, of a pinion connected to rotate the platen, a driver comprising a supporting member and parallel rack-supporting bars extending on opposite sides of said pinion, said bars having a swinging connection with the said supporting member, a toggle link connection between the bars, racks mounted in said bars, cams to swing said bars relatively to the supporting member and hold the racks in operative relation to said pinion during the forward movement of the driver, said cams mounted to swing to inoperative position during the return of the driver, and springs to throw the racks to inoperative position during the return of the driver.
22. In a typewriting machine, the combination with a platen, of a gear connected to rotate the platen, a driver comprising parallel rack supporting bars extending on opposite sides of the driver and racks adjustably mounted in said bars, cams to engage said bars and move them toward each other and hold the racks in operative relation to the driving gear during the movement of the driver in one direction, and means to automatically move the racks to inoperative position and retain them in such position during the return of the driver.
23. In a typewriting machine, the combination with a paper carriage and a roller platen mounted thereon, of a gear connected to rotate the platen, a reciprocating platen driver mounted on the carriage and comprising a rod extending forwardly therefrom and provided with a handle at its forward end, and parallel racks connected to said rod, one in advance of the other and arranged to run on opposite sides of said gear to rotate the platen first in one direction and then in the opposite direction as the driver is advanced.
24. In a typewriting machine, the combination with a paper carriage and a roller platen mounted thereon, of a gear connected to rotate the platen, a reciprocating platen driver mounted on the carriage and comprising a rod extending forwardly therefrom and provided with a handle at its forward end, parallel racks connected to said rod, one in advance of the other and arranged to run on opposite sides of said gear to rotate the platen first in one direction and then in the opposite direction as the driver is advanced, means to hold said racks in operative position during the advance of the driver, and means to automatically hold said racks in inoperative position during the return of the driver.
25. In a typewriting machine, the combination with a paper carriage and a roller platen mounted thereon, of a gear connected to rotate the platen, a reciprocating platen driver mounted on the carriage and comprising a rod extending forwardly therefrom and provided with a handle at its forward end, parallel racks connected to said rod, one in advance of the other and arranged to run on opposite sides of said gear to rotate the platen first in one direction and then in the opposite direction as the driver is advanced, means to hold said racks in operative position during the advance of the driver, means to automatically hold said racks in inoperative position during the return of the driver, a spring to hold the driver in its initial position, said spring being tensioned during the advance of the driver, and a detent to yieldingly hold the driver stationary against the tension of said spring with the driver in an intermediate position in which one of the racks has operated to rotate the platen.
26. The combination with a platen, of a platen driver comprising parallel rack-supporting bars, racks independently supported and adjustable on said supporting bars, and graduated scales on said bars to indicate the positions of the racks on said bars.
27. The combination with a platen, of a platen driver comprising racks, and a pinion to be engaged by said racks and rotated in one direction by one rack, and in the opposite direction by the other rack, said pinion connected to rotate the platen, said driver comprising rack-supporting bars in which said racks are mounted, one of said racks being reversible in its supporting bar for support in inoperative position, whereby the driver may be operated to rotate the platen in one direction only.
28. The combination with a rack bar, of a channel bar in which the rack bar is sup-

ported, and a spring holding clip connected to said rack bar, said clip comprising a lug engageable in notches formed in the channel bar, and thereby holding the rack bar in different positions of adjustment.

29. The combination with a rack bar having a rib extending along one side thereof, of a channel supporting bar in which the rack bar is slidably mounted, said supporting bar formed with a groove to receive said rib, and said supporting bar formed with a series of notches perpendicular to the rack bar, and a spring clip secured to the end of the rack bar and comprising a lug to engage in any one of said notches and hold the rack adjusted.

30. The combination with a platen, of a gear connected to rotate the platen, a platen driver comprising a reciprocating rack supporting and guiding bar, a rack slidably mounted in said bar and operable to engage said pinion and rotate the platen, said rack adjustable along the holding bar, a holding device connected to the end of the rack and comprising means for holding the rack in different positions of adjustment along the bar, said holding device also comprising a holding cam, and a spring detent to engage said cam and hold the driver in a position determined by the adjustment of the rack.

31. In a typewriting machine, the combination with a platen, of a pinion connected to rotate the platen, a platen driver comprising parallel rack-supporting bars arranged to run on opposite sides of the pinion, said bars formed with channels facing the pinion, racks slidably mounted in said channels and provided with rack teeth to

mesh with the pinion, spring holding clips connected to said racks and comprising spring fingers extending upwardly from said channels in position to straddle said pinion, and a holding lug connected to each of said clips to engage in holding notches formed in the channel bars, and thereby hold the racks in adjusted position.

32. In a typewriting machine, the combination with a platen, of a pinion connected to rotate the platen, a platen driver comprising parallel rack-supporting bars arranged to run on opposite sides of the pinion, said bars formed with channels facing the pinion, racks slidably mounted in said channels and provided with rack teeth to mesh with the pinion, spring holding clips connected to said racks and comprising spring fingers extending upwardly from said channels in position to straddle said pinion, a holding lug connected to each of said clips to engage in holding notches formed in the channel bars, and thereby hold the racks in adjusted position, one of said racks being held in advance of the other to cause the platen to be rotated first in one direction and then in the other during the advance of the driver, and one of said holding clips having a cam extension projecting through a slot in the holding bar, and a spring detent to engage said projection when the pinion has been rotated by the first rack.

HERMANN V. FENGLER.
